UNITED STATES PATENT OFFICE.

GUILLERMO DIAZ DEL CASTILLO, OF HABANA, CUBA.

SAFETY RAZOR.

Application filed September 15, 1926; Serial No. 135,659, and in Cuba April 19, 1926.

This invention relates to safety razors and its object is to provide a safety razor of improved construction designed to carry a razor blade that may be used on its four sharpened edges, thus representing a greater duration in the use of each blade.

Another object is to provide a razor blade that though being much wider than those now known, is approximately of the same weight or slightly heavier and can be used on all its four sharpened edges.

A further object is the provision of a razor blade having its four edges sharpened and marked with ordinary characters of reference, so as to show the order in which they must be used.

The invention is described in accordance with the figures of the annexed drawings, in which:

20 Fig. 1 is a side elevation of the safety razor, partly in section on line 1—1 of Fig. 2.

Fig. 2 is a horizontal plan view of the same.

25 Fig. 3 is a top plan view of same, the handle and cover plate of the razor being removed.

Fig. 4 is a detailed perspective view showing the supporting plate of the razor and separately the handle, partly cut-away.

30 Fig. 5 is a detailed perspective view showing the cover plate of the razor; and

Fig. 6 is a detailed perspective view showing the razor blade.

This safety razor presents in a way similar to that already known an arched supporting or bottom plate 1 provided with a central threaded stem 2 and two additional plain stems 3 and 4 in transversal alignment with the threaded stem 2, an arched cover or top plate 5 provided with three holes 6, 7 and 8 transversally aligned and arranged to register vertically with the three stems 2, 3 and 4, and a handle 9 adapted to screw by means of a threaded hollow portion at its lower end, on the center threaded stem 2. But the supporting plate 1 and the cover plate 5 are substantially square in their outline, that is to say, their width equals approximately their length, and supporting

50 plate 1 having its stems 2, 3 and 4 to one side of its middle transverse line at approximately one third of the length of one of its extreme edges, and in a similar way are bored in the cover plate 5 three holes 6, 7 and 8, which are to register with the three stems 2, 3 and 4.

The razor blade 11 is made of a flat flexible plate of a substantially square form, that is to say, its width equals practically its length, and its four edges are sharpened, 60 having a big center opening 12 in order to lighten its weight, this opening being preferably square in section, but with its sides diagonally arranged with respect to the sides of the blade 11, and about that opening 65 12, there are four pairs of holes 13, 13, 14, 14, 15, 15, and 16, 16, in rows parallel to the sides of said opening 12, so that each pair of opposite holes corresponds to the same transverse or longitudinal line, as for instance, 70 a hole 13 in transversal line with a hole 16, a hole 14 in transversal line with a hole 15, and so on, arranged at a distance to each other that equals that between the two side stems 3 and 4. In this way, in curving the 75 razor blade 11 on the bottom plate 1, to conform thereto, two opposite holes transversally aligned for instance, 14 and 15, as pointed out in Fig. 3, will come to register vertically over the two stems 3 and 4, the 80 center stem 2 passing through the center opening 12 of the razor blade 11 close to one of its angles. This will happen in each of the four positions of the razor blade 11 with respect to the bottom plate 1 and the 85 cover plate 5. The curved position of razor blade 11 will be maintained by cover plate 5, when inserted on side stems 3 and 4 over razor blade 11 and then handle 9 is screwed 90 on center stem 2, as is well known.

It will be easily understood that with the holes of razor blade 11 arranged as just explained, the position of same may be so changed that one of the four sharpened edges of the razor blade 11 will always lie 95 on the supporting side of the safety razor.

In order to facilitate the use of the razor blade 11, it is marked on its four sharpened edges with the order numbers 1, 2, 3 and 4, placed closed to the middle of each edge, as 100 shown in Fig. 3, thus permitting that the user of the shaving machine may follow the same order in placing each sharpened edge of the razor blade against the operating side of the razor.

Instead of square blades 11, this razor can be adapted to the use of Gillette or other types of blades.

Having thus described the invention, what I claim is:

1. A safety razor comprising supporting and cover plates and a razor blade placed

between them, all of which are of practically square shape in their outline, the supporting and cover plates having their respective clamping stems and holes to one side of their 5 middle transverse lines, and the razor blade having its four edges sharpened and series of holes distributed in square form so that at least three of them will register vertically with the stems of the supporting plate and 10 the holes of the cover plate in the four different positions that can be adopted by the razor blade.

2. A safety razor comprising bottom and top plates and a razor blade placed between 15 them, all of which are of substantially square shape in their outline, the bottom and top plates having their respective clamping stems and holes to one side of their middle transverse lines, and the razor blade having 20 its four edges sharpened, a big center opening and a series of holes distributed in square form about the center opening, so that in the four positions that can be

adopted by the razor blade, two of said holes will register vertically with the side stems 25 of the bottom plate at the same time that the center stem of same registers vertically with the center opening of the razor blade.

3. A blade for safety razors which consists in a flat plate having its four edges 30 sharpened and having a big center opening of a substantially square form, the sides of which lie diagonally with respect to the sharpened edges of the razor blade, and four pairs of holes arranged about the center opening in rows parallel to the sides of same, so that in each of the four positions that can be adopted by the blade in the safety razor, there may be two holes transversally aligned across the center opening and at a distance between each other that equals the separation between the side stems 35 of the lower plate of the safety razor.

In witness whereof I affix my signature.

GUILLERMO DIAZ DEL CASTILLO.
